Patented July 2, 1912.

UNITED STATES PATENT OFFICE.

GARDNER S. CHAPIN, OF CHICAGO, ILLINOIS.

INTERNAL-COMBUSTION ENGINE.

1,031,245.

Specification of Letters Patent.

Patented July 2, 1912.

Application filed September 28, 1910. Serial No. 584,334.

To all whom it may concern:

Be it known that I, GARDNER S. CHAPIN, a citizen of the United States, residing at Chicago, in the county of Cook and State of Illinois, have invented a new and useful Improvement in Internal-Combustion Engines, of which the following is a specification.

Figure 1 is a transverse section on the line 1 of Fig. 2; Fig. 2 is a side elevation 10 of the engine and Fig. 3 is a section on the line 3 of Fig. 2 looking downward, certain of the parts being shown in central-longitudinal sections.

Referring to the drawings, 10—10 are the 15 cylinders of the internal combustion engine, the same having the usual working parts and being provided with valves of ordinary construction. The intake valves may be automatic but they are preferably mechanically 20 operated in any usual way, for reasons which will presently appear. 11 is a carbureter of ordinary form. Interposed between the carbureter and the intake valves of the engine is a pump-chamber 12, in 25 which, in the preferred form of construction, are two vanes 13 geared together and operating after the manner of the corresponding parts of any rotary-pump. The pump is directly geared to the engine in any 30 obvious manner, its intake-end being connected to the carbureter 11 by pipe 14 and its exhaust-end being connected with the intake of the engine by an intake-manifold 15. The intake and exhaust sides of the pump 35 are connected together by means of a by-pass 16, in which is located a damper or valve 17. The pump is provided with a governor a form of which is shown in Figs. 2 and 3. In this governor one of the pump- 40 shafts carries a sleeve 18 upon which is pivoted an angularly disposed ring 19, held in angular-relation by spring 20, which tends, as the pump shaft is rotated to assume a position at right angles to the axis of said 45 shaft in an obvious manner. The ring 19 is connected by links 21 with a sliding cap 22 on the end of the pump-shaft, the said cap being connected with a lever 23 the opposite end of which controls, through the 50 medium of a link 24, the position of the damper or valve 17. The construction is such that as the pump and engine speed up, the damper or valve will be closed.

The method of operation of my improved 55 device is as follows: It has been found in practice that with engines such as are used

in automobiles and areo-planes, which run at a relatively high speed, that the interval during which the intake valve is open so short and the area of the intake valve opening so small, that only a small fraction of a full charge is taken in at high speed. It has been estimated by a leading authority on automobile construction and practice, that under the usual running conditions, 60 there is drawn through the intake-pipe of an automobile and passed into the cylinders only about one thirteenth of the volume of gas which could be passed therethrough if the engine ran at so slow a speed that the full displacement of the piston in cubic 65 inches would be drawn in each time. This estimate may perhaps be too low, but there is no question but that in ordinary automobile practice a very small fraction of the 70 proper amount of mixture is drawn into the cylinder. This quantity decreases very rapidly as the engine speeds up, so that while at low speed, a comparatively large charge relative to the displacement of the 75 piston may be drawn in, at high speed the charge is relatively low.

In the present device the pump is of such size and is driven at such speed as to maintain upon the intake valve of the engine a 80 sufficient pressure at high speed to remedy to a great extent the present low charge. When the engine is running at high speed the governor holds the valve or damper 17 in the by-pass 16 closed, and therefore the 85 full force of the pump is exerted to maintain this pressure. As the engine runs slower, the by-pass is gradually opened so that the pressure upon the intake valve of the engine falls, until at the lowest possible 90 speed it is maintained at little more than the ordinary atmospheric pressure.

I realize that it has been proposed in the past to provide pumping devices which would augment the charge of combustible 100 mixture supplied to a gas engine. I am not aware, however, that means have ever been provided whereby to increase the effective-pumping action more rapidly than the engine speeds up. In the devices heretofore 105 proposed, the pumps have been directly connected with the engine and if their capacity was greater than that of the cylinder, they pumped in an abnormally great charge at low speed and, of course, a relatively less 110 one at high speed. In this device, however, the arrangement is such that at a low speed

the charge is not augmented to any great extent but at high speed the augmentation becomes progressively greater.

I realize that considerable variation is possible in the details of the construction, without departing from the spirit of my invention; therefore I do not intend to limit myself to the specific form herein shown and described.

10 What I regard as new and desire to secure by Letters Patent is—

1. In combination, an internal combustion engine, a source of combustible fluid, means interposed between the engine and the source of combustible fluid for maintaining in the intake-pipe a gas-pressure above atmospheric-pressure, and means for increasing said pressure as the speed of the engine increases whereby substantially the full gas pressure may be delivered to the engine-cylinder at all speeds of the engine.

2. In combination, an internal combustion engine, a source of combustible fluid, pumping means driven by the engine interposed between the engine and the source of combustible fluid for maintaining in the intake-pipe a gas-pressure above atmospheric pressure, and means for increasing said pressure as the speed of the engine increases whereby substantially the full gas pressure may be delivered to the engine cylinder at all speeds of the engine.

3. In combination, an internal combustion engine, a source of combustible fluid, means interposed between the engine and the source of combustible fluid for maintaining in the intake-pipe a gas pressure above atmospheric pressure, and automatic means governed by the speed of the engine for increasing said pressure as the speed of the engine

increases, whereby substantially full gas pressure may be delivered to the engine cylinder at all speeds of engine.

4. In combination, an internal combustion engine, a source of combustible fluid, pumping means driven by the engine interposed between the engine and the source of combustible fluid for maintaining in the intake-pipe a pressure above atmospheric pressure, and automatic means governed by the speed 45 of the engine for increasing said pressure as the speed of the engine increases, whereby substantially full gas pressure may be delivered to the engine cylinder at all speeds of the engine.

5. In combination, an internal combustion engine, a source of combustible mixture, pumping means driven by the engine and interposed between the same and the source of combustible mixture, a by-pass around the pump, and means by which the effective area 60 of the by-pass may be decreased as the engine speeds up.

6. In combination, an internal combustion engine, a source of combustible mixture, pumping means driven by the engine and interposed between the same and the source of combustible mixture, a by-pass around the pump, governor controlled means for decreasing the effective area of the by-pass as 65 the speed of the engine increases.

7. In an internal combustion engine, means for maintaining a gas-pressure in the intake-pipe above the atmospheric-pressure and for increasing said pressure as the speed 70 of rotation of the engine increases.

GARDNER S. CHAPIN.
